AMMUNITION CONTAINER

George W. O'Hare, Bellflower, and Conrad Harley, Los Angeles, Calif., assignors, by mesne assignments, to Consolidated Vultee Aircraft Corporation, a corporation of Delaware

Application February 26, 1941, Serial No. 380,608

2 Claims. (Cl. 89—33)

The present invention relates generally to ammunition containers. More particularly the invention relates to that type of ammunition container which is used or employed in connection with a machine gun on an airplane and serves as a retaining or holding medium for a cartridge belt.

One object of the invention is to provide an ammunition container which is an improvement upon, and has certain advantages over, previously designed containers of this type or character and is characterized by the fact that it may be loaded or charged with greater facility and in a comparatively short time and is so designed or constructed that the cartridge belt feeds freely and without jamming to the machine gun regardless of the attitude of flight of the airplane with which it is associated.

Another object of the invention is to provide an ammunition container of the aforementioned type which is in the form of an elongated tube and is designed to form a permanent or fixed structural part of the airplane.

Another object of the invention is to provide an ammunition container of the last mentioned character in which the charging end thereof communicates with the exterior of the airplane and has a removable cover which follows and forms a continuation of the contour of the adjacent portions of the airplane and serves to cover the charging end of the container except during a loading operation.

Another object of the invention is to provide an ammunition container of the type and character under consideration in which the discharge end, i. e., the end from which the ammunition belt is fed to the machine gun, is of novel design and is so constructed that the front end of the belt may be readily gripped and fed into the gun when the gun is prepared for use or service.

A further object of the invention is to provide a container which is generally of new and improved construction and not only is light in weight but also is so designed and constructed that it may be produced at a comparatively low cost.

Other objects of the invention and the various advantages and characteristics of the present ammunition container and its charging means will be apparent from a consideration of the following detailed description.

The invention consists in the several novel features which are hereinafter set forth and are

more particularly defined by claims at the conclusion hereof.

In the drawings which accompany and form a part of this specification or disclosure and in which like letters and numerals of reference denote corresponding parts throughout the several views:

Figure 1 is a fragmentary perspective view of an airplane wing having mounted therein a machine gun together with an ammunition container embodying the invention.

Figure 2 is an enlarged vertical longitudinal section of the container illustrating in detail the manner in which it carries or supports the cartridge belt for feed to the machine gun.

Figure 3 is a perspective view showing the construction and design of the chute that constitutes the means for introducing the cartridge belt into the container and illustrating the manner in which the chute is used or manipulated in connection with charging of the container; and

Figure 4 is a perspective view of a part or portion of the cartridge belt.

The container which is shown in the drawings constitutes the preferred form or embodiment of the invention. It is shown in connection with, and as forming a part of, the wing A of an airplane having a machine gun G mounted therein and serves as a retaining or holding medium for a cartridge belt B. The airplane wing A is of standard or conventional design and comprises a front longitudinally extending spar a, a rear longitudinally extending spar a¹ and a series of laterally spaced cross ribs a². Such parts or elements of the wing are surrounded or covered by a skin a³ of metal or other material. The inner ends of the front and rear spars together with certain of the innermost cross ribs define a compartment a⁴ for the machine gun G. Access to this compartment is provided by way of an opening a⁵ in the superincumbent or superjacent portion of the skin a³. This opening is normally closed by a cover plate a⁶, which is removably secured in place by screws or other removable attaching means. The machine gun G is fixedly secured within the compartment a⁴ and extends transversely of the wing A. The barrel of the gun projects forwards and is aligned with, and designed to fire through, an aperture or hole a⁷ in the leading edge of the wing. The cross webs a² have aligned rectangular openings a⁸ in the central portions thereof, i. e., the portions between the front and rear spars a and a¹.

The container is in the form of an elongated

tube and is mounted in, and extends lengthwise of, the wing A. It extends through, and fits snugly within, the openings a^8 in the central portions of the cross ribs a^2 and comprises a top wall 5, a bottom wall 6, a pair of laterally spaced side walls 7 and an inner end wall 8. These walls are formed of plate or sheet metal and are welded or otherwise fixedly secured together. The belt B when stored or in place in the container is arranged in a zig-zag fashion or manner, as shown in Figure 2 and is supported by the bottom wall 6 of the container when the airplane with which the wing A is associated is flying in a normal horizontal position. It is adapted to be introduced into the container through the outer end of the latter, as hereinafter described, and is of conventional design in that it comprises a series of clips which serve to hold, and are interlocked by, the cartridges. The container is riveted or otherwise fixedly secured to the portions of the cross ribs that define the openings a^8 , and serves as one of the structural or reenforcing elements of the wing A. It is located or positioned outwards of the compartment a^4 for the machine gun G and coacts with the spars and cross ribs to reenforce the wing. The outer end of the container constitutes the charging end. It is curved upwards and longitudinally flared, as best illustrated in Figure 2, and communicates with the wing exterior by way of a rectangular opening a^9 . The latter is formed in the portion of the skin a^2 which is disposed directly above the charging end of the container and is normally closed by way of a cover plate 9. The outer ends of the top, bottom and side walls of the container are shaped to form a rectangular flange 10 and this underlies the opening a^9 and is riveted to the portion of the skin which defines such opening. The cover plate 9 corresponds in size to the opening a^9 and is adapted to rest on the flange 10 and seat within or fill the opening a^9 when it is in its closed or normal position. Screws 11 extend through aligned holes 12 in the cover plate 9 and the flange 10 and serve releasably or removably to secure the cover plate in place. The cover plate is of such thickness and contour that when it is in place the outer face or surface thereof follows and forms a continuation of the contour of the adjacent portions of the skin a^2 of the wing. When it is desired to charge the container the screws 11 are removed so as to release the cover plate 9. Thereafter the cover plate is removed in order to render accessible the flared upwardly extending charging end of the container. The outer end of the bottom wall 6 is curved upwards in a gradual manner and terminates at its upper extremity in an out or reverse curve. As a result of this the belt B with the cartridges that constitute the ammunition for the machine gun G slides readily into the container when it is inserted into the opening a^9 . The inner end of the container projects into the gun compartment a^4 and constitutes the discharge end, i. e., the end from which the cartridge belt B is fed to the machine gun. It is shaped or constructed as shown in Figure 2 and includes a substantially tubular discharge guide 13. The upper portion of the inner wall 8 extends outwardly, i. e., towards the charging end of the container at an angle of approximately 45 degrees with respect to the horizontal. As a result of the angular arrangement or position of the upper portion of the inner end wall 8 there is an overhang which so overlies the bends of the cartridge belt at the

discharge end of the container that the strands of the belt, other than the strand nearest the top wall 5, can not become jammed in the inner end of the discharge guide 13 in the event that the airplane with which the wing A is associated is flown upside down or at a sharp angle with respect to the horizontal. The guide 13 extends in parallel relation to the container proper and projects in the direction of, and leads to, the feed box of the machine gun G (see Figures 1 and 2). The inlet end of the guide is joined to the top wall of the container at a point immediately next to the upper portion of the inner end wall 8 and is so shaped that the inlet opening therein is downwardly flared. The top wall of the guide 13 is provided with a longitudinally extending finger slot 14. This slot intersects or communicates with a finger hole 15 in the inner or discharge end of the top wall 5. The finger hole 15 permits the free end of the upper strand of the cartridge belt B to be gripped in connection with loading of the machine gun and the slot 14 permits the person loading the gun to move or feed such free end through the guide 13 to the feed box of the machine gun. The guide 13 is located above the top wall with the result that the portion of the upper belt strand that is immediately beneath the finger hole 15 is separated from, or spaced above, the subjacent portion of the belt. Because of such arrangement of the aforesaid portion of the upper belt strand drag of the upper strand is materially reduced and the belt feeds freely to the machine gun.

For the purpose of charging the container with the cartridge belt B a chute 16 is provided. This chute is of U-shaped cross section and consists of a flat bottom wall 17 and a pair of side walls 18. Said side walls are connected to, and project upwardly from, the side margins of the bottom wall and have out-turned upper flanges 19 for reenforcing purposes. The chute is adapted to hold the cartridge belt B before insertion of the latter into the container. In connection with charging of the container the belt is slid from the chute into the container as illustrated in Figure 3.

Charging of the container is effected in the following manner: First the screws 11 are removed in order to free the cover plate 9. Thereafter the cover plate is removed from the opening a^9 in the skin a^2 of the wing A. After this operation the cartridge belt B is laid in the chute 16 in a zig-zag manner, i. e., in such manner that it has a plurality of superposed strands with connecting bends at the ends of the strands. After loading or charging of the chute one end of the chute is aligned with the outer portion of the opening a^9 . As soon as the chute is properly aligned the belt is slid bodily from the chute into the container. To facilitate sliding of the cartridge belt from the chute a fork 20 is provided. This fork is used by inserting the prongs or tines between the last cartridges of the strands and into straddled relation with the belt. Thereafter the handle is grasped and the fork is moved bodily along the chute. During such movement of the fork the belt is caused to slide from the chute into the container. When the belt is in place in the container the chute is removed and the cover plate 9 is inserted into the opening a^9 and secured in place by the screws 11. After mounting of the cover plate the cover plate a^8 for the gun compartment a^4 is removed. Thereafter the gun is loaded by feeding the free end of the upper strand of the belt through the tubu-

lar discharge guide 13 and into the feed box of the gun, as hereinbefore described. By reason of the fact that the guide 13 is disposed in the gun compartment the finger slot 14 and the finger hole 15 are accessible when the cover plate a⁶ is removed from the opening a⁵. The container, as shown in Figure 6, is downwardly inclined in the direction of the inner end of the wing with the result that the strands, other than the topmost strand, move into engagement with the inner end wall 8 and are locked or held in place by the overhang which is formed by the upper angularly disposed portion of the wall.

The herein described ammunition container is simple as far as design and construction are concerned and hence may be produced at a low and reasonable cost. It effectively and efficiently fulfills its intended purpose and is characterized by the fact that it may be charged with facility and is so designed that there is a free feed of the belt to the gun. The container forms an integral or permanent part of the airplane with which it is associated and constitutes, as hereinbefore described, a structural or reinforcing element for the airplane. It also provides for a maximum ammunition capacity with a minimum size feed hole in the outer or structural surface of the wing allowing for a lighter, more rigid wing structure.

The invention is not to be understood as restricted to the details set forth since these may be modified within the scope of the appended claims without departing from the spirit and scope of the invention.

Having thus described the invention what we claim as new and desire to secure by Letters Patent is:

1. In combination with an airplane wing embodying a series of laterally spaced cross ribs with aligned openings therein and a skin around the ribs with a hole in one portion thereof, and having a machine gun mounted therein, an ammunition container comprising an elongated tube

for a cartridge belt, including rigidly connected top, bottom and side walls, extending through, and fitting snugly within, said openings in the ribs, serving also as a structural or reinforcing part of the wing, having one end thereof open and curved, and in registry and connected relation with the hole defining portion of the skin in order to permit the belt to be inserted into the tube interior from the exterior of the wing, and having its other end provided with a belt guide leading to and terminating adjacent the machine gun, and a removable cover plate for said one end of the tube, shaped conformably to, and fitting removably within, the hole in the skin and forming a part of the wing skin when it is in its normal or operative position.

2. In combination with an airplane wing embodying a series of laterally spaced cross ribs with aligned openings therein and a skin around the ribs and with an opening in the top portion thereof, and having a transversely extending panel closed compartment and a machine gun mounted in said compartment, an ammunition container comprising an elongated tube for a cartridge belt, including rigidly connected top, bottom and side walls, extending through, and fitting snugly within, said openings in the ribs, serving also as a structural or reinforcing part of the wing, having one end thereof open, flared and curved upwards, and in registry and connected relation with the hole defining part of the top portion of the wing skin in order to permit the belt to be inserted into the tube interior from the exterior of the wing, and having its other end provided with a belt guide projecting into the compartment and terminating adjacent the machine gun, and a removable cover plate shaped conformably to, and serving to close, said hole in the upper portion of the wing skin.

GEORGE W. O'HARE.
